UNITED STATES PATENT OFFICE

1,958,310

PROCESS FOR REFINING PETROLEUM
CRUDE OIL

Mert C. McDonald, Coffeyville, Kans.

Application June 27, 1931, Serial No. 547,413

4 Claims. (Cl. 196—18)

This invention relates to improvements in processes for treating petroleum oils for the separation therefrom of amorphous wax, undesirable hydrocarbons, coloring matter, sulphur compounds, and undesirable odors.

The primary object of this invention is the provision of an improved process for the treatment of petroleum oils, for the dewaxing and purification thereof, embodying improvements over the process set forth in prior U. S. Patent #1,791,329, dated Feb. 3, 1931, and granted to Horace B. Seltzer and Mert C. McDonald, in the specific treatment of the hydrocarbon product at a materially lower working temperature for the production of a bright stock of good color and sweet odor having a pour test of from 0° F. to 25° F.

A further object of this invention is the provision of an improved method for the efficient chilling of hydrocarbon oils preparatory to treatment with sulphuric acid for purification.

A further object of this invention is the provision of an improved process for the treatment of petroleum oils, comprising generally the invention of U. S. Patent #1,791,329, heretofore referred to but differentiating thereover, in part, by the chilling treatment of the oils with sulphuric acid at lower temperatures than set forth in said patent and under conditions which will prevent the absorption of moisture during treatment.

Other objects and advantages of this invention will be apparent during the course of the following detailed description.

In the accompanying drawing, forming a part of this specification, similar reference characters designate corresponding parts throughout the view.

The view generally designates, in diagrammatic manner, the apparatus which is preferably used for the dewaxing and purification treatment of petroleum oils.

The apparatus consists of a storage tank A for receiving the crude petroleum oil, with which a discharge line 10 is connected. A pump 11 in the line 10 pumps the oil through the line 10 and into a tank 11a. A main still 12 is provided, preferably of the horizontal tank type, into which the crude petroleum oil flows through a reflux tower 14 which has connections 15 with the tank 11a thereabove, and which

at its lower end has a conduit connection 18 with the still 12. If desired, the tower 14 may be provided with ordinary rectification or reflux baffles. A vapor line 20 leading from the top of the still extends into the intermediate portion of the tower 14, and the vapors passing through the tower 14 and into the tank 11 will distill off or vaporize from 5 to 10% of the initial stock, for the purpose of dehydration.

In the still 12 the petroleum oil is heated to substantially 250° F. and is then transferred to a cooler 21 including a casing 22 with a cooling coil 23 therein. The cooling coil 23 is connected by a conduit 24 with the lower portion of one end of the still 12, and in this conduit 24 is disposed a pump 25 for pumping the heated oil through the coil 23. From the coil 23 the oil is pumped into a combination chiller and treating apparatus 30 which includes a tank 31, of any approved metal, shaped with an upper cylindrical portion and a lower funnel-shaped bottom 33. Throughout its major height the tank 31 is surrounded with a jacket 34 spaced from the walls of the tank 31 to define a brine receiving jacket space 35 wherein brine is disposed, to surround the tank 31 below the bottom and throughout its major height. The tank 31 and its surrounding jacket 34 are entirely insulated externally, preferably by means of cork 33.

The discharge end of the coil 23 enters the upper end of the tank 31 at 39, for depositing the pre-cooled petroleum oil into the compartment or chamber 40.

The center of the tank bottom 33 has a discharge pipe or conduit 42 through which the sludge as well as the purified desirable oils, are withdrawn.

Sulphuric acid is introduced into the upper part of the tank through a conduit 45, and together with the petroleum oil is mixed within the chamber or compartment 40 by an improved mechanical agitator. The latter includes a main shaft 43 extending axially through the tank. At its lower end it has a step bearing 44 in the tank upon the bottom 33; the same being supported by a suitable spider as shown in the drawing. The shaft 43 extends vertically through the tank and exits at the top therefrom. It has a main agitator 48 in the cylindrical portion of the tank, which consists of a plurality of paddles adapted

- to perform the main mixing action. In the conical space at the bottom of the tank there is a small agitating blade 49, in the shape of an ordinary propeller which accomplishes the final mixing of the petroleum and sulphuric acid. 5
- Means is provided to drive the shaft 43 which consists of a motor 50 having a shaft 51 connected by bevel gearing 52 with the upper end of the shaft 43. 10
- Brine cooling apparatus is provided for maintaining the brine in the space 35 at a predetermined temperature. This apparatus includes a cooling tank 55 having inlet and discharge conduits 56 and 57 for the cooling medium. A brine 15 cooling coil 58 is disposed within the tank 55, having a discharge conduit 59 connected with the lower portion of the brine jacket space 35 for discharging the cold brine into the space 35. A brine discharge conduit 60 connects with the upper portion of the tank brine space 35, having a discharge end connected in the preferably insulated brine storage tank 61. The latter has a conduit connection 62 with the inlet end of the brine cooling coil 58, and in this conduit 62 is disposed a pump 63 for circulating the brine. 20
- A conventional thermometer 65 may be provided on the apparatus 30 for designating the temperature of the contents within the compartment 40. 25
- It is an important feature of the invention that the mixing of the sulphuric acid and petroleum oil shall take place within a comparatively air-tight compartment. To that end the tank 31 is entirely enclosed during treatment, although it 30 may have a man-hole construction 65^a with a suitable cover 66 to seal over the same. At times it may be desirable to vent a small quantity of air into the compartment 40 to discharge vapor for reducing superatmospheric pressure in the 35 compartment 40. To that end a vent conduit 67 is connected with the top of the tank having a weight controlled vent valve 70 communicating therewith which is operable responsive to pressures within the tank for the escape of air or 40 gas for relieving such pressure. The conduit 67 may also have a low pressure valve 71, of the weight operated variety, which will open responsive to certain sub-atmospheric pressures within the tank to vent a small quantity of air into the 45 tank. These vent valves prevent the rupture or collapsing of the tank under unusual circumstances. 50
- The discharge line 42 has a branch connection 55 for conveying the lighter oil constituents, after dewaxing and purification, to any suitable location. The line 42 also enters the top of a sludge tank 77. This tank 77 has an external jacket 78 which provides a steam space 80 surrounding the lower portion of the tank for elevating the 60 temperature of the sludge as it is received from the mixing apparatus 30. Suitable inlet and outlet connections 81 and 82 are provided, with valve controls for regulating the passage of steam through the jacket space 80. Stirring apparatus 65 is provided in the sludge tank 77 which is suitably operated by motor means 87 from externally of the tank. A conduit 90 connects with the upper portion of the tank 77 for conveying wax oil into a suitable storage tank 91; the line 90 having a pump 92 therein. The lower portion of the sludge tank 77 has a sludge line 93 connected therewith which is provided with a pump 94 therefor for pumping the sludge to a suitable burner 97 beneath the still 12, so that the sludge residue 70 may be used as fuel for heating the still 12. 75

As before stated, the crude oil is charged into the still, after having distilled off from 5 to 10% of the light hydrocarbons, in order to insure that the oil to be later purified will be free of moisture. This vapor distillate passes off from the tank 11 through the line 100. The oil remaining in the still has a temperature of approximately 250° F. and is then conveyed through a cooling coil 23, wherein the temperature is gradually reduced to approximately 80° F. at the time that the same passes through the conduit 39 into the top of the compartment 40. 80

It is highly important in the improved process to prevent shock chilling. This for the reason that if the oil to be purified is chilled too rapidly it will require a higher percentage of sulphuric acid for purification. I have found that it will require as much as 25 pounds more sulphuric acid per barrel of oil to be purified if the latter is subject to shock chilling instead of a gradual chilling. The oil to be purified as it enters the compartment 40 of the treating apparatus 30 is protected from exposure to the atmosphere, since the compartment 40 is air-tight. This prevents absorption of moisture from the atmosphere. 85

Moisture will dilute sulphuric acid, generating heat and generally hindering the chilling for low temperature purification treatment. 95

The chilling apparatus 30 preferably has a motor 50 which is of a variable speed type in order that the agitator may be driven at a moderate speed while the oil is being cooled preparatory to sulphuric acid treatment, and later speeded up to increase the agitation while the purification treatment of the oil with concentrated sulphuric acid 100 is being carried out. 105

The temperature at which the acid treatment of the oil in the tank 31 is carried out preferably ranges between -30° F. and 25° F. I have found these to be the most practical working temperature extremes in order to secure a purified oil 115 which will respond to a desired flow test. 115

Assuming that the tank 31 is charged with 1000 barrels of mixed base crude oils that have substantially a gravity of 32 A. P. I. Assuming the same to have just entered the tank 31 and being at a temperature of 80° F. the variable speed motor 50 is set in operation, and the agitators 48 and 49 run at moderate speed. The brine is circulated through the jacket surrounding the jacket 31, by the means above described, and precaution is taken to see that the temperature of the brine refrigerant is maintained within 15° F. to 20° F. of the actual temperature of the oil being chilled in the tank 31. This precaution is taken, 120 at least until the oil in the tank 31 has reached a freezing temperature after which it is chilled down rapidly. This precaution will prevent the shock chilling above referred to. The lowering of the temperature of the 1000 barrels of selected oil in the tank 31 will require approximately 12 hours. When the zero temperature, or the required low temperature of the oil in the tank 31 has been reached, the variable speed motor 50 is increased to speed up the agitators 48 and 49, 125 130 and the concentrated sulphuric acid is then pumped or otherwise discharged into the compartment 40 at the approximate rate of 300 pounds per minute. After approximately 25,000 pounds of concentrated sulphuric acid has been discharged into the tank compartment 40, the severe agitation of the oil coming into contact with the concentrated sulphuric acid will bring about the desired reaction. The sludge collecting in the bottom of the tank compartment 40 will form ap- 135 140 145

proximately 21% of the total charge. In the example above given this will comprise about 210 barrels. In this 210 barrels of sludge there are associated petrolatum, sulphur compounds, coloring matter, and other undesirable constituents and characteristics, such as the heavier ingredients and the odor attendant therewith. Approximately six hours after the agitators have been stopped, the sludge will represent approximately 220 barrels of the contents and may be readily drawn off into the tank 77. The petrolatum will represent approximately 60 barrels of the sludge residue thus obtained and may readily be separated from the remaining constituents of the sludge by agitation and mixing at a temperature of approximately 125° F. The latter elevation of temperature is of course obtained by passing steam through the jacket 78. The petrolatum is then conveyed into the wax tank 91 to be used as pressure still cracking stock, or for the removal of other ingredients and by-products. The residue sludge may be pumped through the line 93 and used as fuel for heating the still 12, as above mentioned.

25 After the sludge has been drawn off from the tank 31 there will remain substantially 780 barrels of dewaxed and purified petroleum oil. This is now discharged from the apparatus through the line 75 and conveyed to a suitable agitator 30 wherein the said oil is neutralized under temperatures of substantially 120° F. The neutralization treatment is carried out by agitating the oil and mixing therewith a suitable neutralizing agent such as fuller's earth, soda ash, ammonia, or the like. In event fuller's earth is used it will be required in the proportion of 15 pounds per barrel of oil, and subsequent to proper mixing and agitation the oil will be passed through a filter press for removing the neutralizing agent from the oil, which of course contains the acid which it has absorbed.

40 After the neutralizing treatment the residue oil may be distilled for removing the different hydrocarbons. The first group which may be distilled off will be commercially finished gasoline; the second group commercially finished kerosene; the third group commercially finished gas oil; the fourth group lubricating light motor oil. The residue heavier group of hydrocarbons, known as heavy commercial finished bright stock will have a very low pour test. Generally I have found that the cloud test on the dewaxed and purified petroleum oil will be approximately zero and the color approximately 4 N. P. A. The distillation when carried out will result in approximately 20% gasoline; approximately 20% kerosene; approximately 15% gas oil; approximately 10% paraffin oil; approximately 15% low pour test light motor oil, and the residue 20% of heavy bright stock product will have approximately a 160 to 165 viscosity at 210° F. with a pour test of from 5° F. to 15° F., a bright color at 0° F., and a gravity of 5½ N. P. A.

45 The principal advantage of the process and apparatus is the flexibility of operation which will enable a refiner to operate his plant according to the needs of a shifting market so far as pour tests of the lubricating oils and bright stock are concerned. The public demands a much lower pour test oil in winter than in summer, and of course it is much less expensive to produce a bright stock with a pour test of 15° F. to 30° F. than to produce a bright stock ranging between 0° F. and 15° F. pour test.

50 To illustrate that various results are obtained

by using various temperatures, as well as by using different diluted oils after distilling off substantially 8% of light hydrocarbons, I have prepared a number of examples, which are as follows:—

	1	2	3	4	5	6	
Viscosity at 210° F. of above	48	48	48	48	48	48	85

Color of last above (N. P. A.)	5½	5½	5	6	6	

135 It will readily be understood that the above examples are not to be construed as a limitation upon my improved process, for it is a fact that each particular treating temperature, and the characteristics of the crude oil require analysis for determining the amount of acid necessary. I do treat petroleum crude oils for dewaxing and purification at temperatures below those previously used for the object of producing commercially finished products, and motor oils with a low pour test.

140 Various changes in the steps of the method herein outlined, as well as changes to the arrangement of parts of the apparatus, may be made to the method and apparatus as herein 145

150

described, without departing from the spirit of the invention or the scope of the claims.

I claim:

1. Those steps in the method of treating petroleum oils containing amorphous wax, which consist in gradually reducing the temperature of the selected oil to between -30° F. and -5° F. with moderate agitation, treating the oil with concentrated sulphuric acid during speeded-up 10 agitation, thereby to precipitate substantially all of the wax and sludge, and thereafter drawing off the waxy sludge.

2. In a process of treating crude petroleum oil containing amorphous wax for the production 15 of a bright stock oil having a pour test ranging from substantially 0° F. to 25° F. and without the use of an added diluent, the step of subjecting said oil while at a temperature of between -30° F. and -5° F. to a treatment with concentrated sulphuric acid in a system closed to 20 the atmosphere, until the amorphous wax therein is precipitated.

3. The process of producing from a residue of

crude oil a bright stock oil having a pour test between 0° F. and 25° F. which includes dehydrating and topping the crude oil, chilling the dehydrated and topped oil to an effective dewaxing temperature, subjecting the dehydrated chilled oil to a treatment with concentrated sulphuric acid while excluding air and moisture from the atmosphere therefrom until substantially all wax is precipitated, separating the wax from the treated residue, and neutralizing the treated residue. 85

4. The steps in the process of treating petroleum crude oil which consist in gradually chilling the crude oil in a chamber to an effective dewaxing temperature, subjecting the oil to a treatment while in said chamber with concentrated sulphuric acid until substantially all wax has precipitated from the crude oil, and drawing off the sludge from the treated oil while maintaining the oil out of contact with the atmosphere from the beginning of chilling until substantially all wax is precipitated. 90 95
